UNITED STATES PATENT OFFICE.

W. BRITTON LANE, OF EVANSTON, ILLINOIS, ASSIGNOR OF ONE-HALF TO UNIVERSAL RAILWAY SUPPLY COMPANY, OF CHICAGO, ILLINOIS, A CORPORATION OF ILLINOIS.

CUSHIONING MEANS FOR RAILWAY-CARS.

1,087,305.

Specification of Letters Patent. Patented Feb. 17, 1914.

Application filed June 4, 1912. Serial No. 701,496.

To all whom it may concern:

Be it known that I, W. BRITTON LANE, a citizen of the United States, and a resident of Evanston, in the county of Cook and 5 State of Illinois, have invented a certain new and useful Improvement in Cushioning Means for Railway-Cars, of which the following is a description, reference being had to the accompanying drawing, which forms 10 a part of my specification.

My invention relates more particularly to means whereby a pneumatic cushion will be provided for railway-cars, the means being so constructed that the elastic medium or 15 air may be supplied by the usual air line of the train.

The object of the invention is the provision of means whereby an easier riding car is produced, which will be practically free 20 of the shocks and vibration encountered where the usual truck springs alone are employed; and whereby the lateral swaying of the car due to unevenness in the road bed will be practically eliminated through the 25 absorption of the motion by the cushioning means mounted on opposite sides of the car, thereby also greatly relieving the rails and ties from the shocks and stresses to which 30 they are subjected with the present existing constructions.

In the drawings:—Figure 1 is a cross section of the lower part or bottom of a car, illustrating one of the trucks in elevation and showing the application of my invention. 35 Fig. 2 is a vertical sectional view taken on the line 2—2 of Fig. 1 looking in the direction of the arrows. Fig. 3 is a horizontal sectional view taken on the line 3—3 of Fig. 2. Fig. 4 is a detail view showing 40 the valve mechanism in perspective.

In the drawing and Fig. 1, 5 represents the usual longitudinal sills of the car arranged beneath the floor 6, with my improved cushioning means shown applied between the two longitudinal side sills of the car at opposite sides thereof; the device being preferably arranged intermediate of the longitudinal sills of the car and the car bolster 7, which latter is mounted above the 45 truck bolster 8, with the usual center bearing 9 arranged between the two bolsters.

As my invention does not relate to the construction of the truck or car, a specific description of the truck will not be entered 50 into, as the invention is adapted for use in

connection with the type of truck and car body at present in use.

The invention consists in providing one or more cylinders 10 at both sides of the car body at points coincident with the trucks. 60 The side walls of the cylinders may be provided with the flanges 11, 11, which are adapted to extend beneath the adjacent longitudinal sills 5 and secured thereto in any suitable manner as illustrated for example 65 in Fig. 1. The cylinder 10 is preferably provided at a suitable point intermediate of its ends with an escape port or opening 12, see Fig. 2, while the side of the cylinder facing lengthwise of the car is preferably 70 provided with a valve chamber 13, which is connected with the conduit or pipe 14 which connects with the usual air line of the car. The valve chamber has communication with the cylinder interior through the port 15. 75 The chamber 13 is provided with a suitable sliding valve as shown at 16 adapted to move in a vertical direction therein.

Cylinder 10, which is shown with its lower end open, is provided with a suitable piston 80 17. The piston 17 is adapted to be secured to, or rest on the ends of the car bolster 7, as shown in Fig. 1. The piston 17 is provided with suitable packing rings or glands 85 18 so as to provide an air tight sliding connection between the piston and the walls of the cylinders. The piston 17 is provided with an extension or lug 19 which has a suitable opening to receive the stem 20 of valve 16. In the construction shown in the 90 drawing, this stem 20 is shown screw threaded to receive nuts 21, whereby the relation between the piston and the valve may be controlled.

In the application of my invention, one 95 or more cylinders are arranged between the longitudinal sills of the car body at points preferably above the ends of the car bolster; the cylinders being secured to the longitudinal sills as previously described, while the 100 pistons are placed on the ends of the car bolster, and if desired, may be secured thereto. The valve chamber 13 is then connected with the air line of the train by means of pipe 14, so that air may flow into chamber 105 13 and be allowed to pass into cylinder 10, which is made possible by reason of the fact that valve 16 will be in the upper part of chamber 13 until air has entered cylinder 10 and forced the piston. 110

With the valve 16 in the position shown in Fig. 2, it is evident that the flow of air into cylinder 10 will be shut off. Unless the cylinders 10 are filled with air, it is apparent that the pistons 17 will be forced into the cylinders until they are in contact with the upper or end wall of the cylinders. With the pistons moved up into this position, it will be seen that the valve 16 will be compelled to move upward in valve chamber 13 in a similar manner by reason of the connection between the piston and valve. When the valve 16 has been moved toward the upper end of the valve chamber 13, the hollow portion 16^a of the valve will be brought opposite the point of communication between the valve chamber 13 and air line 14, thus permitting the elastic medium or air to flow into valve chamber 13 passing about the valve and entering the cylinder 10 through port 15. The port 15, as shown in Fig. 2, is preferably arranged so as to discharge at the upper end of the cylinders, so as to insure the air being discharged intermediate of the wall of the cylinder and the piston. As soon as a sufficient quantity of air has been allowed to flow into the cylinders 10, it is evident that the relative position between the cylinder and piston will be altered so as to move the piston toward the lower end of the cylinder as shown in Fig. 2. This movement of the piston will, by reason of its connection with valve stem 20, move valve 16 downward and close off the points of communication between the air line 14 and cylinder 10.

In practice, it may be found desirable to provide air line 14 with a suitable check valve as shown at 22, and also with a bypass 40 as indicated at 23; the check valve 22 being so arranged that it will close against the return flow of the medium or air from the cylinder, while the bypass 23 will permit of a gradual seeping or return so as to relieve excess pressure in the cylinders and thereby provide the desired cushioning effect or degree of resilience.

With the construction shown and described, it is apparent that the car will be provided with a medium of the greatest resiliency in addition to the usual springs with which the truck is provided; the device being used as an auxiliary cushioning means without necessitating a change in the construction of truck or car body. The cushioning means will be automatic in operation and so arranged that a uniform depth of air cushion will be maintained while the car is in service. As is clearly apparent, should the car sway from one side to the other, the downward pressure of the car-body will tend to permit a greater quantity of the elastic medium or air to flow into the cylinder at that side of the car which is tilted beneath the normal level of the car, while

the lifting or upward movement of the opposite side of the car will close off the flow of air to the cylinders at that side of the car which is above the normal level, so that a substantially uniform depth of air cushion will be maintained.

The bypass 23 will permit the air to seep or pass back into the air line of the train and thus prevent its escape, at the same time relieving the pressure in the cylinders during excessive compression.

If the flow of air into the cylinders should be too great before the valves have been moved below the inlet port of the valve chamber, by reason of a leaky valve or otherwise, the relation between the piston and cylinder will be affected so as to bring the piston below port 12 and allow the air in the cylinders to escape into the atmosphere, until the pressure in the cylinders has been relieved and the piston allowed to pass upward within the cylinder beyond the port 12. A pneumatic cushion is thus provided in addition to the usual springs employed in the trucks, and the cushion is obtained by utilizing some of the air supplied through the air line of the train as previously described; but the air supply may be had in any desired manner, and the construction shown and described may be altered in certain details without however departing from the spirit of my invention. I do not wish, therefore, to be understood as limiting myself to the exact construction shown and described, but

What I claim and desire to secure by Letters Patent is:—

1. Means of the class described, comprising a cylinder adapted to be secured to a car body, said cylinder being provided with inlet and outlet ports, the inlet port being arranged adjacent to one end of the cylinder while the outlet or escape port is arranged at a point intermediate of the ends of the cylinder, a piston adapted to be secured to the car bolster of a truck and slidably mounted in said cylinder and arranged to close said escape port until said piston moves toward one of the ends of the cylinder, a valve chamber having communication with the inlet port of the cylinder and with a source of air supply, said points of communication being arranged in different planes, and a valve slidably mounted in said valve chamber and adapted to be operated by said piston.

2. Means of the class described, comprising a vertically disposed cylinder adapted to be secured to a car body, said cylinder being provided with an inlet port and an escape port, the inlet port being arranged in the side wall of the cylinder so as to communicate with the cylinder interior immediately adjacent the inclosed end thereof, while the escape port is arranged in the side

wall of the cylinder at a point intermediate of the ends of the cylinder, a piston adapted to be secured to the car bolster of a truck and slidably mounted in said cylinder so as to close the escape port when the piston occupies a position above the plane of the escape port, a valve chamber integral with one side of the cylinder and with which the inlet port communicates, said valve chamber having communication with a source of air supply or other elastic medium, the point of communication with the air supply and the inlet port to the cylinder being arranged in different horizontal planes, and a double piston valve slidably mounted in said valve chamber and so arranged that it may occupy a position intermediate of the inlet port of the cylinder and the point of communication with the air supply, said valve having adjustable connection with said piston so as to move vertically therewith.

3. Means of the class described, comprising a vertically disposed cylinder adapted to be secured to a car body, the side walls of the cylinder being provided with an inlet port and an outlet port arranged in different

horizontal planes, the inlet port being arranged to communicate with the cylinder at a point adjacent the end wall thereof, a valve chamber integral with the cylinder and surrounding said inlet port, said valve chamber having a supply line communicating with a source of air supply or other elastic medium, the supply line communicating with the valve chamber at a point occupying a different horizontal plane from that of the inlet port, means located in said supply line whereby compression within the cylinder may be controlled, a piston adapted to be secured to the car bolster of a truck and slidably vertically in said cylinder and arranged to move across the escape port, and a piston valve slidably mounted in the valve chamber and adjustably connected with said piston so as to move therewith and adapted to occupy a position intermediate of the inlet port and the point of communication with the supply line.

W. BRITTON LANE.
